UNITED STATES PATENT OFFICE

LEONARD WESTPHALEN, OF CHICAGO, ILLINOIS

PHOTOGRAPHER'S TWIN-ARC LAMP

Application filed November 30, 1928. Serial No. 322,788.

My invention relates to arc lamps of the type commonly employed by photographers; and more particularly to an improved construction of a foldable reflector, and to novel 5 means for controlling the feeding of the carbons and the restarting of the arcs in a twin-carbon arc lamp.

In one of its general aspects, my invention aims to provide a lamp having the source 10 of light disposed within a forwardly open casing from which four forwardly flaring reflector wings project when the lamp is in use; aims to provide an arrangement which will permit these wings to be folded compactly into the casing when the lamp is not in use; and aims to provide simple and 15 easily released connections whereby certain of the wings interlock when in use, so that the wings will form a rigid four-winged 20 reflector disposed in effective position with respect to the source of light.

Furthermore, my invention aims to provide a lamp with two cooperating reflectors, one of which is readily foldable, and aims 25 to provide simple means for holding the other reflector in fixed disposition.

In still another aspect, my invention aims to provide simple means for controlling the 30 clutches in a twin-carbon arc lamp through a slideable control rod, and for insulating both the control rod and the rod-retracting spring from the casing of the lamp.

Still further and also more detailed objects will appear from the following specification and from the accompanying drawings, 35 in which

Fig. 1 is a front elevation of a twin-carbon arc lamp embodying my invention, with the reflector wings opened out and interlocked 40 as they appear when the lamp is in use.

Fig. 2 is a horizontal section, taken along the line 2—2 of Fig. 1.

Fig. 3 is a front elevation, drawn on a smaller scale than Fig. 1 and showing the 45 reflector wings in their folded positions.

Fig. 4 is a fragmentary horizontal section taken along the line 4—4 of Fig. 3, but drawn on a larger scale.

Fig. 5 is a front elevation, drawn on the 50 same scale as Fig. 1, showing one pair of

reflector wings extended while the other is folded ready to be swung into the casing, a portion of one wing of the latter pair being broken away.

Fig. 6 is a perspective view showing the 55 end portions of two adjacent reflector wings which are arranged for releasably interlocking with each other.

Fig. 7 is an enlarged and fragmentary section transverse of the casing, showing an 60 alternative arrangement of the carbon-feeding mechanism.

In the illustrated embodiment, the rectangular box-like casing of my lamp is a forwardly open casing having sides 1, a 65 top 2 and a bottom 3 extending forwardly from the back 4 of the casing, this casing being supported from its sides by a swiveling stirrup 5 mounted on the riser 6 of a stand. Extending across the casing parallel 70 to its back is an insulating plate 7 which supports the usual resistance coils 8 in the space behind it, this space being ventilated by apertures 9 in the casing. Fastened to the vertical insulating plate 7 are two forwardly extending brackets 10, each of which carries a clamp 11 for supporting one of the lower (and normally stationary) carbons 12; while a horizontal insulating plate 13 rests on the bottom 3 of the casing and extends 75 below the carbon clamps 11 and the carbons 12 to prevent these carbons from being slid down against the bottom of the casing.

Each of the upper carbons 14 extends slidably through a vertical sleeve 15 depending 80 from a horizontal bar 16 which is supported from the vertical insulating plate 7 by two brackets 18. The bar also carries two riser stems 19, each of which has a stop ring 20 fastened to it at some distance above the bar 16.

For starting the arcs, I provide a control rod 21 extending slidably through the bottom insulating plate 13 and the bar 16, a 85 rocker bar 22 pivoted at its middle to the upper end of the rod 21 and a link 23 depending from each end of the rocker bar. Each link 23 extends downwardly through the inner end portion of a clutch bar 24 90

100

through which one of the upper carbons 14 and the adjacent riser 19 also extends.

A spiral compression spring 25 encircles a lower portion of the control rod 21 and rests at its lower end on the bottom insulating plate 13, while the upper end of this spring is hooked through a perforation in the said rod 21, and a knob 26 of insulating material is fastened to the rod 21 below the bottom of the casing. The spring 25 is of such length that it will normally raise the rod 21 to a position in which each clutch bar 24 tilts upward toward the rod 21, thereby causing each upper carbon to be lifted by the grip of the clutch bar through which it extends.

When the tips of the carbons have been consumed sufficiently to rupture the arc (or at least to lengthen either one of the arcs unduly), the user pulls the control rod 21 down against the pressure of the spring 25, thereby loosening the grip of each clutch bar on the carbon 14 which extends through that bar. Each upper carbon then slides down by gravity against the tip of the lower carbon, after which the downward pull on the handle 26 of the control rod is released, thereby permitting the spring to lift both this rod and the clutch bars again, so as to provide new spacings between each vertically aligned pair of carbons. The bottom 3 of the casing has a perforation considerably larger than the diameter of the rod 21, so that the latter is out of contact with the casing and hence does not electrically connect the casing with the upper carbons.

To project the light of the two arcs effectively, I employ two reflecting means, one of which is a stationary reflector 27 formed approximately as a portion of an upright tube having its axis considerably forward of both arcs. This curved reflector 27 may be a simple curved metal sheet, formed so that when its back engages the vertical insulating plate, the side edges of the reflector snap respectively behind the hinging portions of the side wings 28 and 29 of the wider mounted folding reflector and these side edges of the reflector press laterally against the inner faces of the side walls 1 of the casing.

Each of the four wings of the folding and forwardly flaring reflector is shaped like a frustum of a triangle, and the two side wings 28 and 29 are hinged at their shorter vertical edges directly to the casing, respectively at the forward edges of the two side walls 1. Each of the companion wings is hinged at one end of the adjacent end of one of the side wings and adapted to fold against the inner face of the side wing to which it is hinged, while the free end of each of the said companion wings is arranged so that it will releasably interlock with the unhinged end of the side wing adjacent to it. Thus, the drawings show the top wing 30 as hinged

to the upper end of the side wing 28 and adapted to be swung against the inner face of the latter, while the lower wing 31 is hinged to the lower end of the side wing 29 and adapted to be swung against the face of the last named side wing.

Moreover, both the hinging and the said interlocking provisions are arranged so that the folded wings can be swung into the front of the casing (as shown in Figs. 3 and 4) so as to compact the lamp for shipping or storage.

As a simple arrangement for the releasable interlocking of one end of each side wing with an end of one of the companion (upper or lower) wings, I desirably provide special formations only on the free ends of one interhinged pair of reflector wings, while leaving the free ends of the other two interhinged wings void of any special formations.

Thus, the side wing 29 (which is hinged to the right hand side wall of the casing as viewed in the drawings) is perfectly flat except for the hinged formation which connects it to the similarly flat bottom wing 31. On the other hand, the left-hand side wing 28 is provided at its lower end with fingers extending at right angles to the face of that wing and consecutively offset from each other so that the free end of the lower wing 31 can slip and wedge between them—namely, two outer fingers 32 and an interposed inner finger 33. Similarly arranged fingers also project from the free end of the upper wing 30 in the same general direction, namely at right angles to the face of the wing and forwardly when the reflector is assembled.

With the wing 30 slightly shorter than the side wing 28 to which it is hinged, the finger portions of these will pass each other, so that these interhinged wings can be folded and swung into the casing as shown in Fig. 4, with the other pair of interhinged wings (29 and 31) swung upon each other swung across the mouth of the casing in front of the wings 28 and 30. When the lamp is to be used, each folded pair of wings is swung outward and unfolded, after which each set of the interlocking fingers has the adjacent end of another wing slipped between them, thereby forming a rigid but readily releasable reflector assembly.

Since the reflector when folded (as in Figs. 3 and 4) is disposed entirely within the mouth of the casing, I greatly reduce the size of box required for shipping any lamp and also reduce the space required for storing the lamp when not in use, besides avoiding the risk of damage to a projecting reflector. Moreover, since the four parts of my foldable reflector are easily formed of sheet metal, they cost less than a spun reflector. And by suitably proportioning the reflector parts, I can secure a light distribu-

tion which is fully as effective (for the illumination of subjects that are to be photographed) as that obtained with a spun reflector, since a reflector with two sides extending in the same direction as the carbons of the lamp produces less deviation in the light distribution with a shifting of the arc or arcs than will occur with a spun reflector.

At the same time, my simple carbon control mechanism permits a convenient shortening of the arcs after their tips are somewhat worn, without requiring any touching of the hot carbons or of metal parts connected to the circuit. Consequently, my invention in its various aspects provides a relatively inexpensive, cheaply shipped and highly effective lamp which can readily be used even by amateurs.

However, I do not wish to be limited to the use of my twin-arc control mechanism, in combination with the novel reflector arrangement here disclosed, nor to the use of a particular form of central reflector in combination with my foldable reflector, nor to the use of my foldable reflector in connection with two arcs. Neither do I wish to be limited to the details of the construction and arrangement here disclosed, as changes may obviously be made without departing either from the spirit of my invention or from the appended claims.

I claim as my invention:

1. In a lamp, a forwardly open casing having upright sides; two pairs of reflector wings, each pair comprising a side wing and a transverse wing hinged at one end of a side wing, the hinges of the two wings in the two pairs being respectively at the upper end of one side wing and at the lower end of the other side wing, means associated with the free end of each side wing for releasably latching the same to the free end of one of the transverse wings; two hinges respectively connecting each side wing with the mouth end of one of the upright sides of the casing, the said hinges projecting laterally inward of the said sides, an auxiliary reflector bowed about a vertical axis and having its side edges respectively engaging the said casing sides behind the two hinges, and means within the casing engaging the back of the auxiliary reflector to press the said edges of the auxiliary reflector against the hinges.

2. In a lamp, a forwardly open casing; and a foldable forwardly flaring reflector comprising four wings, namely two side wings respectively connected by hinges at their inner ends to the casing, a top wing hinged at one end to the upper end of one side wing, and a bottom wing hinged at one end to the lower end of the second side wing; the free end of each side wing being releasably interlocked with the free end of the wing which is hinged to the other side wing; and an auxiliary reflector disposed within the casing and retained in the casing by the said hinges.

wing; the hinging of the side wings to the casing being effected by hinges disposed so that when the top and bottom wings have been swung respectively flatwise against the side wings to which they are hinged, the resulting pairs of folded wings can be swung into the casing with one pair thereof in front of the other pair.

3. In a lamp, a forwardly open casing; and a foldable forwardly flaring reflector comprising two pairs of interhinged wings, namely two side wings respectively connected by hinges at their inner ends to the casing, a top wing hinged at one edge to the upper end of one side wing, and a bottom wing hinged at one edge to the lower end of the second side wing; the top wing and the bottom wing each having at the edge opposite the hinging edge a flange extending at an angle to the main portion of that wing and disposed for engaging the outer face of the side wing opposite to that to which the said top or bottom wing is hinged, and also having adjacent to its outward edge a finger engaging the inner face of the side wing engaged by the flange on the same top or bottom wing to clamp a portion of the last named wing against the said flange.

4. In a lamp, a forwardly open casing; and a foldable forwardly flaring reflector comprising two pairs of interhinged wings, namely two side wings respectively connected by hinges at their inner ends to the casing, a top wing hinged at one edge to the upper end of one side wing, and a bottom wing hinged at one edge to the lower end of the second side wing; the top wing and the bottom wing each having at the edge opposite the hinging edge a row of flanges extending in the same direction at an angle to the main portion of that wing, the flanges in each row being in staggered planes spaced approximately by the thickness of one of the side wings, so that a portion of the side wing adjacent to these flanges may be inserted between the flanges of that row when the reflector is unfolded.

5. In a lamp, a forwardly open casing; and a foldable forwardly flaring reflector comprising four wings, namely two side wings respectively connected by hinges at their inner ends to the casing, a top wing hinged at one end to the upper end of one side wing, and a bottom wing hinged at one end to the lower end of the second side wing; the free end of each side wing being releasably interlocked with the free end of the wing which is hinged to the other side wing; and an auxiliary reflector disposed within the casing and retained in the casing by the said hinges.

6. In a lamp, a forwardly open casing; and a foldable forwardly flaring reflector comprising four wings, namely two side wings respectively connected by hinges at

their inner ends to the casing, a top wing hinged at one end to the upper end of one side wing, and a bottom wing hinged at one end to the lower end of the second side wing; the free end of each side wing being releasably interlocked with the free end of the wing which is hinged to the other side wing; and an auxiliary reflector mounted within the casing and formed substantially as a part of an upright tube, the spread of the auxiliary reflector being greater than the width of the wings of the aforesaid flaring reflector to permit the flaring reflector to be swung into the mouth of the reflector after the said top and bottom wings have respectively been swung against the said side wings.

Signed at Chicago, Illinois, November 26th, 1928.
